Nelson M. Howard

UNITED STATES PATENT OFFICE.

FRANK H. LATINVILLE, OF BROCkTON, MASSACHUSETTS, ASSIGNOR TO UNITED SHOE MACHINERY COMPANY, OF PATERSON, NEW JERSEY, A CORPORATION OF NEW JERSEY.

SHOE.

1,172,467.

Specification of Letters Patent. Patented Feb. 22, 1916.

Application filed June 14, 1915. Serial No. 33,956.

To all whom it may concern:

Be it known that I, FRANK H. LATINVILLE, a citizen of the United States, residing at Brockton, in the county of Plymouth and State of Massachusetts, have invented 5 certain Improvements in Shoes, of which the following description, in connection with the accompanying drawings, is a specification, like reference characters on the drawings indicating like parts in the several figures.

This invention relates to boots and shoes and more particularly to improvements in the type of shoes known as "plain toe" 15 shoes which have a vamp extending in one piece over the entire toe portion of the shoe. In the manufacture of this type of shoe it is impractical to secure the box toe materials to the vamp by through and through 20 stitches or to form a pocket to receive such materials as is done in making the styles of shoes in which a toe tip is sewed to the vamp since the stitches for securing the box toe materials would appear on the outside of 25 the vamp and thus spoil the desired effect of the plain toe of the shoe. It is also unsatisfactory to cement the box toe materials to the vamp because the cement often stains the vamp and sometimes so stiffens it as to 30 prevent it from being properly lasted and, moreover, cement is not a permanent fastening but allows the box toe materials to work loose during the wear of the shoe. The usual practice is to place the box toe materials loosely between the vamp and the shoe lining. This practice, however, is far 35 from satisfactory because while the shoe is being pulled-over or being lasted the box toe materials frequently become displaced relatively to the vamp and lining thus requiring 40 the pulling-over machine operator or the laster to stop and re-position the box toe materials. Such displacement detracts from the appearance of the finished shoe and 45 sometimes produces a distorted condition of the box toe materials within the shoe which is not readily discovered during the manufacture of the shoe or which renders the shoe uncomfortable to the wearer.

50 The present invention has for an object to improve the appearance and the fit of plain toe shoes and enable such shoes to be manufactured more expeditiously and with greater uniformity than the present practice permits. This is accomplished by per-

manently securing the box toe materials against displacement in the toe of the shoe by fastening means herein shown as single faced stitches which do not detract from the appearance of a plain toe shoe. The stitches 60 extend through the box toe materials along the upper transversely extending edge of the materials and extend from the inside face of the vamp only partially through the vamp leaving the outer surface of the vamp 65 uninterrupted and unbroken.

An important feature of the invention consists in a shoe having a vamp which extends in one piece over the entire toe portion of the shoe combined with box toe materials 70 permanently secured to the inner side of the vamp by means which extend through a portion of the vamp but do not appear on the outer surface of the vamp.

Other objects and features of the invention will appear from the following description when considered in connection with the accompanying drawings and will then be pointed out in the claims.

In the drawings:—Figure 1 is a perspective view of a vamp in which the invention is embodied in the preferred form; Fig. 2 is a detailed perspective illustrating the manner of securing the box toe materials to a vamp; and Fig. 3 is an enlarged section 80 on the line 3—3 of Fig. 2.

Referring to the drawings, 2 represents the style of vamp used in the manufacture of plain toe shoes and to which the present invention is particularly applicable. This 90 style of vamp extends in one piece over the entire toe portion of the shoe and forms an uninterrupted or unbroken surface for the forepart of the shoe.

In accordance with this invention the 95 box toe materials herein shown as comprising a sheet 4 of stiffening material and a cover piece 6, are properly positioned between the vamp 2 and the shoe lining 8, the upper edge of the sheet 4 and its cover piece 100 extending transversely across the toe portion of the vamp in the usual manner. The box toe materials are secured by blind or single faced stitches 12 along their upper edges 10 to the inner side of the vamp 2, as 105 shown in Fig. 2. These stitches 12 extend from the inside face of the vamp only partially through the vamp thus leaving the outer surface of the vamp uninterrupted and unbroken. This operation may be per- 110

formed upon any of the well known blind stitch sewing machines now in use and at little additional cost to the manufacturer. With the box toe materials permanently secured to the vamp before the shoe upper is assembled on the last, no further attention on the part of the operator is required during later operations on the shoe to prevent the box toe materials from being displaced 5 in the shoe with the result that the shoe is handled and operated upon more readily and with greater facility than the present practice permits. Furthermore the finished 10 shoes present a more shapely and uniform appearance and they are more comfortable for the wearer. Also the outer surface of 15 the vamp at the toe remains unbroken and uninterrupted so that the desired plain toe effect for the toe portion of the shoe is secured. 20

Having described my invention, what I claim as new and desire to secure by Letters Patent of the United States is:—

1. A shoe having a vamp which extends 25 in one piece over the entire toe portion of

the shoe combined with box toe materials secured to the inner side of said vamp by single faced stitches which extend through the box toe materials and the vamp but which do not appear on the outer surface 30 of the vamp.

2. A shoe having a vamp which extends in one piece over the entire toe portion of the shoe, and box toe materials permanently secured to the inner side of said vamp by 35 means extending through a portion of the vamp but which do not appear on the outer surface of the vamp.

3. A shoe having a vamp which extends in one piece over the entire toe portion of 40 the shoe, box toe materials positioned on said vamp and having an upper edge extending transversely of the vamp, and single faced stitches permanently securing said box toe materials to said vamp along 45 said transversely extending edge.

In testimony whereof I have signed my name to this specification.

FRANK H. LATINVILLE.
